UNITED STATES PATENT OFFICE.

THOMAS WEBBER COTTLE, OF TOPEKA, KANSAS.

CABINET SCRAPER-HOLDER.

1,135,361.

Specification of Letters Patent. Patented Apr. 13, 1915.

Application filed March 24, 1914. Serial No. 826,982.

To all whom it may concern:

Be it known that I, THOMAS WEBBER COTTLE, a citizen of the United States, residing at Topeka, in the county of Shawnee and State of Kansas, have invented a new and useful Cabinet Scraper-Holder, of which the following is a specification.

The device forming the subject matter of this application is a holder adapted to retain a scraper, and one object of the present invention is to provide novel means for clamping the scraper adjustably in place.

Another object of the invention is to provide a device of this type in which the scraper holding head may be detached readily.

Another object of the invention is to provide novel means for limiting the pivotal movement of the head with respect to the handle portion of the device.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawing:—Figure 1 shows the invention in side elevation; Fig. 2 is a fragmental longitudinal section; Fig. 3 is a perspective of the head; Fig. 4 is a side elevation showing a portion of the handle; Fig. 5 is a perspective of the scraper; Fig. 6 is a perspective of that portion of the device which is delineated in Fig. 4.

In carrying out the present invention there is provided a handle 1 equipped at its outer end with a transverse cam or arm 2 which is terminally provided with oblong trunnions 3, the cross sectional dimensions of the trunnion being indicated at 4 and at 5. Projecting from the handle 1 is an ear 6, into which is threaded a screw 7.

The scraper holding head is of arched form and is indicated at 8, the head 8 comprising an intermediate portion 9 and arms 10. In the arms 10 are journaling openings 11 which receive the trunnions 3, there being reduced slots 12 in the edges of the arms 10, which slots 12 communicate with the openings 11.

The scraper 14 may be of any desired

form and is bound between the intermediate portion 9 of the head 8 and the fixed cam 2 on the handle 1.

In practical operation, the handle 1 is turned until the trunnions 3 lie approximately parallel to the length of the slots 12. Then the trunnions 3 are slid through the slots 12 into the openings 11. Then relative pivotal movement is produced between the handle 1 and the head 8 until the cam 2 binds against the scraper 14. When the cam 2 is thus in binding relation with the scraper 14 the cam will compress the scraper against the intermediate portion 9 of the head 8, the trunnions 3 will stand crosswise of the slots 12, and thus a disengagement of the handle from the head will be prevented. In order to shift the position of the scraper 14 it is necessary merely to tilt the head 8 on the handle until the cam 2 loosens its hold on the scraper, and then the scraper may be adjusted. The pivotal movement of the head 8 with respect to the handle 1 is limited by the screw 7 which engages the rear face of the scraper 14. The screw 7 has another function, in that if the scraper 14 be bound so closely against the intermediate portion 9 of the head 8 as to render the pivotal movement of the head 8 difficult, the screw may be manipulated to swing the head 9 on the trunnions 3 and thus effect a release of the cam 2 from the scraper 14.

It is to be noted that when the head 8 is tilted slightly to release the hold of the cam 2 on the scraper 14, the oblong trunnions 3 will prevent the head 8 from becoming detached from the trunnions, it being possible to detach the head from the handle only when the scraper 14 stands in approximate parallelism with the handle.

If desired, adjusting elements such as screws 25 may be mounted in the cam 2. When a scraper blade approximating the thickness shown in Fig. 2 is employed the screws 25 are retracted, but when a thinner scraper blade is used, the screws 25 may be advanced slightly thereby to increase the eccentricity of the cam and to make the cam effective as a holding means.

Having thus described the invention, what I claim is:—

1. A scraper embodying an arched head comprising side arms having journal apertures, the side arms being provided in their edges with reduced slots which open into the journal apertures; and a handle includ-

ing a cam coöperating with the head to form a blade holding means, the cam having ob-
long trunnions insertible into the journal
5 apertures through the slots when the handle
is swung to move the cam out of coöperative
relation with respect to the head, the trun-
nions bridging the inner ends of the slots to
hold the handle and the head assembled
10 when the handle is swung to bring the cam
into coöperating relation with respect to the
head.

2. A scraper embodying an arched head;
a handle including as a rigid structure, a
grip and a transverse cam, the cam being
15 terminally journaled in the head and co-

operating with the head to form a blade
holding means, the handle including an ear;
a movable element in the ear and forming a
stop for the head; and movable means in
the cam adjacent its ends for varying the 20
eccentricity of the cam, the said movable
means being adjustable independently of
the grip portion of the handle.

In testimony that I claim the foregoing
as my own, I have hereto affixed my signa- 25
ture in the presence of two witnesses.

THOMAS WEBBER COTTLE.
